COMBINED PACKAGING TRAY AND COVER

Kenneth W. Artz, Mohnton, Pa., assignor to
W. R. Grace & Co., Duncan, S.C.

Filed Dec. 17, 1968, Ser. No. 15,023

Term of patent 14 years

Int. Cl. D9—04

U.S. Cl. D9—219

FIG. 1

FIG. 2

Des. 220,752

PAGE 3

FIG. 4

FIG. 1 is a perspective view of a combined packaging tray and cover showing my new design;

FIG. 2 is a top plan view thereof;

FIG. 3 is a section taken on line 3—3 of FIG. 2 on an enlarged scale; and

FIG. 4 is a side elevation thereof on the same scale as in FIG. 3.

I claim:

The ornamental design for a combined packaging tray and cover, substantially as shown.
